CLEANING UNIT FOR AUTOMOBILES

Oren B. Harmes, Algona, John H. Threlkeld, Britt, and Donald A. Deal, Algona, Iowa

Filed July 18, 1960, Ser. No. 61,408

Term of patent 14 years

(Cl. D9—2)

Fig. 1 is a front perspective view of a cleaning unit for automobiles showing our new design.

Fig. 2 is a side elevational view thereof.

Fig. 3 is a rear elevational view thereof; and

Fig. 4 is a top plan view thereof.

The side not shown is substantially like the side shown.

We claim:

The ornamental design for a cleaning unit for automobiles, as shown and described.
